ARTIFICIAL TOOTH AND MOUNT
THEREFORJacob A. Saffir, New York, N. Y., assignor to The
Dentists' Supply Company, New York, N. Y., a
corporation of New York

Application November 17, 1943, Serial No. 510,651

4 Claims. (Cl. 32-9)

This invention relates to improvements in artificial teeth and mounts therefor. It more particularly relates to teeth of the interchangeable or replaceable type. Such teeth are adaptable for use in crown and bridgework in general. The teeth of this invention have certain important advantages when used in fixed bridgework and may be used in various kinds of removable bridgework with equal advantage.

There has long been a need in the art for teeth and bridgework that have adequate strength and which will minimize or keep down the display of metal, such as gold or stainless steel, of which the framework of the bridge is commonly composed. This unsightly display of metal has been objectionable as observed in the contact areas between the teeth, at the incisal edges or on the occlusal surfaces, or even on the lingual side and becomes most conspicuous and evident when the patient's mouth is opened as may be exemplified while talking, laughing or yawning. For a long time there has also been a need for an interchangeable tooth structure that would be more sanitary and hygienic when in actual use and when in continuous service in the mouth. To those familiar with the art it is known that artificial teeth in bridgework frequently become objectionably discolored, primarily because of the disintegration and washing away of the dental cements, thus allowing ingress to medicines, tobaccos and other compositions that leave stain deposits. Moreover, under such washed out conditions, bacteria and food particles lodge in such spaces to the detriment of the patient's health and to the offensiveness of a bad breath toward others. Such oral conditions are breeding places for certain types of disease germs that may, through certain avenues, undermine the patient's health, such as through the blood stream or the digestive tract.

Because of the ineffectualness of dental cements, interchangeable teeth of the prior art have frequently become loosened or completely uncemented. This has too commonly resulted in breakage or even in complete loss of the tooth structure, whereby embarrassing the patient and impairing the mastication of food. Moreover, such tooth losses have inconvenienced the patient and added to his expense of time and repair. This loss of time and the expense of repair is often costly because the damage may be extensive enough to necessitate the dentist constructing an entire new bridge.

Many of the interchangeable types of bridge teeth of the past have presented an objectionable

feeling to the patient's tongue. In some instances this has been an undesirable sensation of artificiality whereas in other instances they have caused impairment of the patient's speech. Most of these bridge teeth as manufactured heretofore have to one degree or another been comprised of metal on the lingual side and usually porcelain on the labial or buccal side. These two different types of composition have different thermal properties and different surface textures and each composition differs from the patient's natural teeth. The metal in this instance is the least easy to keep clean and from time to time will accumulate certain undesirable surface deposits and discoloration. All of this tends to accentuate the feeling of artificiality. Further, in fitting the interchangeable artificial teeth to the metal framework of the bridge and to the metal lingual portion, contours are frequently objectionably interrupted, or the two compositions will present sharp abruptness or poor fit at their junctural margins resulting in objectionable roughness, or the size of the complete artificial tooth may be wrong to one degree or another and/or in one dimension or another, much of which readily contributes to adversely affect speech and may be conducive to lisping, whistling, poor enunciation or poor pronunciation.

A certain amount of controlled translucency has also been desired in artificial teeth but this has been offset and to some degree nullified by the opacity of dental cements. Substantially all of the dental cements designed and recommended for crown and bridge tooth cementation have possessed this objectionable opacity. While I am aware that certain of the so-called "synthetic cements" have possessed translucency to one degree or another yet these products were not designed for tooth cementation. In fact they were actually designed for a filling material to be used in filling cavities in natural teeth. Moreover, they were designed to be mixed to a heavy putty-like consistency wherein a precise amount of dry synthetic cement powder is mixed with a rather definite amount of the liquid, all of which is recommended by the manufacturer of the product. Now when cementing crowns and bridge teeth this putty-like consistency of synthetic cements is so heavy that the tooth structure cannot be satisfactorily seated on its backing or support. If the amount of liquid is increased in the powder-liquid ratio, thereby obtaining a more fluid creamy-like mix, then the physical properties of the synthetic cements are upset and the results are unsatisfactory. Moreover, synthetic cements

under these conditions of thin mix lack the required amount of adhesive properties. Therefore, dental cements of the past, to an appreciable degree, have failed to provide proper translucency when used in attaching bridge teeth.

By virtue of my improved artificial tooth structure and mount constituting the present invention, I have overcome all of the above shortcomings of the prior art.

It is, therefore, one of the objects of my present invention to provide an integral one-piece interchangeable artificial tooth or pontic formed from a suitable plastic.

Another object of my invention is to provide an interchangeable artificial tooth formed from plastic having a depression, recess, or slot formed in a side or sides of the body thereof for the reception of a mounting permitting the application of the tooth to a bridge structure which may be already located in the mouth of the patient.

A further object of the invention is to provide an interchangeable slotted or recessed plastic artificial tooth of the foregoing character, in which the slot or recess is filled with a monomer-polymer of the plastic from which the tooth body is formed to secure the tooth to the mounting, and wherein the filling plastic monomer-polymer becomes an integral, homogeneously molecularly-united part of the tooth plastic to provide an integral, homogeneously molecularly-united one-piece plastic artificial tooth structure.

Another object of the invention is to provide an interchangeable artificial tooth formed from plastic material, in which the previously formed and shaped plastic tooth is capable of application to a mounting located in the mouth of the patient, and in which means is provided for completing the plastic tooth to a finished structure within the mouth of the patient whereby to provide a one-piece plastic tooth formed throughout from the same kind of plastic material.

Another object of my invention is to provide an interchangeable one-piece plastic tooth whose exterior surfaces are substantially all tooth-simulating.

Another object is to provide an interchangeable artificial tooth formed from plastic and a mounting therefor, in which the plastic of the tooth penetrates and extends through spaces or openings formed in the mounting in the finished tooth structure.

A further object of my invention is to provide an improved interchangeable artificial tooth structure formed from plastic, and an improved mounting therefor, which is of simple and durable construction, relatively inexpensive to manufacture, and one which may be quickly and readily installed directly in the mouth of the patient by normal methods and technique.

Another object of my invention is to provide an improved interchangeable artificial tooth formed from plastic which affords a good match as to size and color with the other artificial or natural teeth in the patient's mouth.

Another object of my invention is to provide improved mounting means for supporting the plastic tooth of my invention.

A further object is to provide mounting means of improved nature, so shaped and formed as to be particularly well adapted for receiving and permanently supporting the integral one-piece plastic tooth of my invention in improved manner.

Generally speaking, my present invention re- 75 Figure 2, looking in the direction of the arrows.

lates to the production of an interchangeable artificial tooth formed from a suitable plastic, and an improved mounting therefor, in which the tooth is preferably formed in a suitable separable mold and of substantially its final size, configuration and type, the tooth being provided while in the mold with a suitable depression, recess or slot which is adapted to receive one of my improved mountings to permit the plastic tooth to be attached as a permanent part of a bridge structure already installed in the patient's mouth.

In accordance with my invention the major body portion of the molded plastic tooth is applied to the mounting and secured permanently thereto by the application of a minor body portion of monomeric plastic, similar to the plastic from which the body of the tooth is formed, to the depression, recess or slot formed in the tooth body, which minor body portion of monomeric plastic will copolymerize with the plastic of the major body portion and penetrate through openings or spaces formed in the mounting to become bonded with the plastic of the major body portion to provide a one piece homogeneously molecularly-united tooth structure whose exterior surfaces are all substantially tooth-simulating and which tooth structure is free from cracks, crevices or joints.

Further, and in accordance with my invention 30 a suitable solvent and also a suitable catalyst are employed with the monomeric plastic, the former serving to soften the plastic of a wall or walls of the depression, recess, or slot to effect a bonding of the two plastics, and the latter, namely the catalyst, assisting or accelerating the action of polymerization of the two bodies or masses of similar plastic to provide the molecularly-united homogeneous plastic tooth structure. It will be understood that the quantity of catalyst employed determines the time required for polymerization.

Moreover, and also in accordance with my invention, improved mounting means or members are employed which have anchor portions so shaped and constructed, or formed as to substantially fill the depression, recess or slot provided in the plastic tooth and which, by virtue of their novel structure, including suitable spaces, openings or depressions formed therein, permit the plastic of the tooth to penetrate same and form an intimate bond with the embedded anchor portion of the mounting to ensure the permanent securing together of the tooth and mounting against accidental separation or loosening.

The foregoing and other objects and advantages of my invention will appear from the following description and appended claims when considered in connection with the accompanying drawings forming a part of this specification wherein like reference characters designate corresponding parts in the several views.

In said drawings:

Figure 1 is a vertical longitudinal sectional view of a two-part mold, with the parts thereof separated, for producing one type or style of plastic artificial tooth or pontic in accordance with the present invention.

Figure 2 is a vertical longitudinal sectional view of the mold of Figure 1 with the parts in closed position and showing an artificial tooth embodying my invention located in the mold cavity.

Figure 3 is a plan view of the lower half of the mold taken substantially along the line 3-3 of Figure 2, looking in the direction of the arrows.

Figure 4 is a perspective view of a plastic artificial tooth formed in the mold of the preceding views.

Figure 5 is a vertical longitudinal sectional view of a three-part mold for producing teeth in accordance with the present invention, the parts or sections thereof being shown separated.

Figure 6 is a vertical longitudinal sectional view of the mold of Figure 5, showing the parts of the mold in closed position and with a plastic tooth embodying the present invention located in the mold cavity.

Figure 7 is a perspective view of an interchangeable plastic artificial tooth embodying the invention and produced by the mold of Figures 5 and 6.

Figure 8 is a perspective view of an improved mounting embodying my invention for use in connection with the plastic tooth of Figure 7.

Figure 9 is an elevational view of the lingual face or side of the tooth of Figure 7 showing the mounting of Figure 8 associated therewith.

Figure 10 is a vertical sectional view taken substantially along the line 10—10 of Figure 9, looking in the direction of the arrows and showing the tooth after its application to the mounting of Figure 8 and with the minor body portion of monomeric plastic located within the mounting depression, recess or slot.

Figure 11 is a view similar to Figure 10 showing the tooth after the polymerization action has started.

Figure 12 is a view similar to Figures 10 and 11 and showing the plastic tooth of those figures after the completion of the process of polymerization, the tooth body presenting a one-piece homogeneous, molecularly integral plastic structure.

Figure 13 is a perspective view, partly broken away, of the lingual side or face of the tooth of Figure 12 showing in detail the action of polymerization of the plastic in the region of the mounting openings or spaces.

Figure 14 is a front elevational view of an upper arch showing a partial bridge structure therein and illustrating the manner of applying the tooth of Figure 7 to a mounting of the bridge structure.

Figures 15, 16 and 17 are vertical sectional views of plastic artificial incisors showing several different forms and locations of mounting-receiving depressions, recesses or slots formed therein.

Figures 18 to 30, inclusive, are perspective views of various modified forms or types of artificial tooth mountings embodying my present invention.

Before explaining in detail the present invention it is to be understood that the invention is not limited in its application to the details of construction and arrangement of parts illustrated in the accompanying drawings, since the invention is capable of other embodiments and of being practiced and carried out in various ways. It is to be understood also that the phraseology or terminology employed herein is for the purpose of description and not of limitation, and it is not intended to limit the invention herein claimed beyond the requirements of the prior art.

Referring now to the drawings and particularly to Figures 1, 2 and 3 thereof, I have shown a suitable two-part mold for producing the major body portion for a one-piece plastic artificial tooth or pontic such as that shown in Figure 4.

A lower or bottom mold section 31 is provided with a mold cavity formed in sections, as shown at 32 and 33, which are separated by an upstanding projection, wall or rib 34 which extends transversely between the cavity sections and which, as best seen in Figure 3, is of irregular outline or shape. The upper portion or section of the mold is shown at 35 and is provided with a single cavity 36. The lower mold section 31 is, as shown, provided with a guide pin socket 31a and with an upstanding guide, locating or centering pin 31b, the former to receive a guide pin 35b carried by the upper mold section 35 and the latter being adapted to fit within a guide socket 35a formed in the mold section or portion 35 for the purpose of properly and accurately aligning the mold cavities when the sections are placed together. As shown, the lower mold section 31 is adapted to form the lingual face, surface or portion of the artificial tooth, such as that shown as a whole at 37 in Figure 4, whereas the upper mold section 35 is adapted to form the labial face, surface or portion of the artificial tooth 37.

The mold sections 31 and 35 are preferably formed from bronze or brass although they may, if desired, be made of plaster of Paris, artificial stone or Bakelite.

The projection or rib 34 is provided for the purpose of forming, in the lingual side of the tooth 37, a depression, recess or slot such as that shown at 38 in Figure 4 for the purpose of receiving the anchor portion of a mounting member for the artificial tooth, as will be presently described.

In making an artificial tooth or pontic, such as the tooth 37, with the two-part or two-piece mold, I preferably provide the mold with a doughy monomeric plastic, such as methyl-methacrylate, which is placed in the lower half 31 of the mold after which the upper or top half 35 thereof is assembled with the lower half. If desired, a plastic of more than one color may be used; in fact, as many different colors may be packed into the mold cavity as is desired. For example, if a two-color tooth is to be produced, I employ one color for the incisal and enamel portions and another color for the body portion of the one-piece plastic artificial tooth. The plastic is packed in the mold with a slight surplus to allow for any shrinkage which might occur during polymerization and the mold parts or sections are closed together slowly and then preferably placed in a spring press which will apply a continual pressure to the mold until such time as the methyl-methacrylate has been completely cured. The parts of the mold are then separated and the artificial tooth 37 removed therefrom.

Referring now particularly to Figures 5 and 6 of the drawings, I have shown in these figures a suitable three-part mold for producing a tooth, such as the tooth shown in Figure 7.

The mold of Figures 5 and 6 comprises an upper section or portion 39 constituting the labial half of the mold, the lingual half of the mold being formed in two separable mold sections or parts 40 and 41. The labial portion or face of the artificial tooth is formed in the depression or recess 39a of the labial half of the mold, whereas the lingual side or portion of the tooth is formed in the cooperating depressions or cavities 40a and 41a of the mold sections 40 and 41, respectively. It is to be noted that the mold portion or section 41 is provided with an inwardly and longitudinally projecting tongue member 42

which, when the parts 40 and 41 are placed together, is located within the cavity 40a.

The mold section 39 is provided with a guide pin-receiving recess or socket 39b and with a guide pin 39c, the former being adapted to receive a guide pin 41c carried by the mold section 41 and the latter being adapted to fit within a pin-receiving socket or recess 40b formed in the inner face of the mold section or portion 40. The section 40 is also provided with a guide pin-receiving recess or socket 40c for the purpose of receiving a guide or locating pin 41b carried by the mold section 41.

To produce the tooth shown as a whole at 43 in Figure 7 in the mold of Figures 5 and 6, the lower mold sections 40 and 41 are placed together and their cavities 40a and 41a have applied thereto a doughy monomeric plastic, such as methyl-methacrylate, after which the upper or top mold section 39 is placed in position upon the lower sections 40 and 41, as seen in Figure 6. If desired, more than one color plastic may be used; in fact, plastics of several different colors may be packed into the mold cavities 40a and 41a so as to produce different portions of the finished artificial tooth in different colors, if desired. The plastic is preferably packed into the mold cavities with a slight surplus to allow for any shrinkage that might occur during polymerization and after the mold parts are brought together in closed position slowly, they are preferably placed in a spring press for the purpose of applying a continual pressure to the mold parts until such time as the methyl-methacrylate has been completely cured. With the three-part mold of Figures 5 and 6, when the sections 40 and 41 constituting the lingual half of the mold are clamped together, theoretically, these associated parts together with the labial part or section 39 of the mold, constitute a two-part mold to pack with the plastic in the same manner as the two-part mold of Figures 1 and 2 is packed.

When opening the mold of Figure 6 after curing of the plastic artificial tooth 43, the labial half or section 39 of the mold is first removed, after which the incisal lingual portion or section 40 of the mold is moved away from the section or portion 41, whereupon the finished tooth 43 is slipped off the tongue 42 of the gingival section or portion 41 of the mold. The finished tooth 43 is provided, as shown, with a depression, recess or slot 44 which extends inwardly from the gingival lingual portion of the tooth toward the incisal lingual portion thereof, and provides means for the reception of one of my improved mountings which will be presently described.

It will be understood that other types of molds may be employed for producing the novel tooth or teeth of my invention.

Referring now particularly to Figures 7 to 14, inclusive, of the drawings, I have shown in these figures a tooth 43 such as that formed in the mold of Figures 5 and 6, together with a suitable mounting for location within the recess or slot 44 of the tooth, and have also illustrated the action which occurs during the forming of an integral one-piece plastic artificial tooth after the mounting has been received in the tooth recess or slot, as well as one mode or manner of applying the tooth 43 to the mounting forming a part of a bridge structure.

In Figure 8 there is shown one form of suitable mounting embodying my present invention.

As shown, this mounting is formed from some suitable metal and comprises a frame 45 having two generally triangularly shaped interconnected portions 46. Each of these frame portions has a space or opening 47 formed therein and it will be noted that the mounting is provided with another space or opening 48 located between the sections 46. The mounting is adapted to be received in the slot 44 of the tooth 43 and when in position with relation to said tooth, as seen in Figure 9, the projection 43a of the tooth will fit within the space 48 of the mounting.

Referring now particularly to Figure 14 of the drawings, there is shown in this figure an upper arch structure, indicated as a whole at 49, and several natural teeth 50 forming a part thereof. A bridge structure is mounted between the abutment natural teeth 50, this bridge being shown as a whole at 51. The bridge, as shown, consists of four secured-together mountings such as the mounting 45 of Figure 8. In accordance with the structure shown in Figure 14, one of the plastic artificial teeth 43 of the incisor type has been applied to one of the mountings 45 adjacent one of the natural teeth of the arch, there being shown a second artificial tooth 43 in the process of being applied to another of the mountings 45.

In accordance with my invention, and by way of securing the major body portion of the plastic artificial tooth 43 to the mounting 45, I preferably apply a monomer type bonding medium or material, which is the same as the plastic from which the artificial tooth portion 43 is formed, to the mounting 45 to substantially fill the openings 47 therein, some additional bonding material also being applied to the slot 44 of the tooth. The monomer type bonding medium or material constitutes what I designate the minor body portion shown at 52 in Figure 10 after the tooth 43 has been slipped into position over the mounting 45. In addition to the monomer, I employ a catalyst in the form of an oxidizing agent, such as benzoyl peroxide, which may be used in proportion, by weight, of the monomer in from 0.10 to 0.50 per cent. The bonding material is prepared for use by adding a definite amount of the catalyst to the monomer and causes the walls of the tooth defining the slot 44 therein to return to a temporary soft stage as a result of the solvent action, the catalyst causing the bonding material and the temporarily softened plastic of the slot walls to set or polymerize. This setting may be accelerated if desired by the application of heat at a temperature of approximately 122° F. One manner in which the heat may be applied is by means of the application of a warm spatula which is held against the artificial tooth. The bonding material and the material of the softened walls of the tooth will flow together so that polymerization will cause a loss of identity of the bonding material and it will appear, upon examination, as a homogeneous part of the tooth wall indistinguishable from the tooth wall itself, except perhaps for a difference in color which can be remedied by coloring the bonding medium to completely effect its loss of identity.

As stated above, the monomer bonding material or medium constituting the minor body portion of the tooth-forming element immediately after its application to the mounting and the slot in the major body portion of the artificial tooth-forming element, is represented at 52 in Figure 10. This same material is shown after

it has commenced to set or polymerize, at 53 in Figure 11, whereas, after the material has set or completely polymerized in the region of the reference character 54 of Figure 12, the identity of the minor body portion has been completely lost, the material having become an integral homogeneous part of the tooth structure and thus indistinguishable from the plastic of the tooth 43, as is clearly seen in the cross sectional view, Figure 12 of the drawings.

It will be understood that some of the monomer type bonding material is applied to the groove or slot 44 above the top frame portion of the mounting 45 so as to completely fill this space and to produce a seal or covering above the mounting, it being understood, of course, that the monomer polymerizes with the adjacent walls of the tooth body at this point and also becomes an integral part of the tooth structure to conceal the mounting, as seen at 55 in Figure 12. Thus, by concealing the mounting, all surfaces or faces of the artificial tooth become substantially tooth-simulating.

For the purpose of showing more clearly how the monomer type bonding medium constituting the minor body portion of the tooth-forming element may flow to become an integral part of the final plastic tooth structure, I have shown some of the minor body portion penetrating the spaces of the mounting 45, as represented by the reference character 54 in Figure 13 of the drawings.

As a result of the polymerization of the minor body portion of bonding monomer shown at 52 in Figure 10, in complementing contiguity with the rigid completely polymerized pre-formed major body portion of the plastic artificial tooth structure, it will be understood that the mounting is not only concealed but that the tooth 43 will become positively locked or anchored onto the mounting.

In practice, the walls of the slot 44 are in intimate contrast with and are coated by the complementing minor body portion of as yet non-completely-polymerized monomer type bonding medium and this monomeric medium, sufficiently thickened, penetrates the openings 47 and 48 forming the latticework-like mounting 45 bonding molecularly with the walls of the slot 44 and mechanically keying into the anchoring surfaces of the mounting member. After this association of the monomeric medium, the artificial tooth 43 is placed in position upon the mounting, as illustrated in Figure 14, and held in such position until the bonding material has polymerized sufficiently to hold the tooth firmly without danger of movement. The patient is then instructed not to chew or eat food for a period of time up to two or three hours, or until such time as the monomeric medium will have become sufficiently polymerized to resist, without injury, the stresses of mastication. It will be understood that the amount of catalyst added to the monomeric medium will determine the time required for setting or polymerization, a smaller amount of catalyst being used if relatively slow setting is desired, or a greater amount of catalyst employed if rapid setting or polymerization is desired.

It will be understood that the artificial tooth 43 is applied to the mounting 45 directly in the mouth of the patient, it being unnecessary, by virtue of my invention, to apply the tooth to the mounting outside the mouth of the patient.

If any of the monomeric bonding material should accidentally become lodged upon parts of

the labial or other surfaces of the tooth where it is not desired or needed, this excess or surplus can be easily and quickly removed by prompt action before it has had an opportunity to set.

Referring now particularly to Figures 15, 16 and 17 of the drawings, I have shown in these figures three incisor type plastic artificial teeth made in accordance with my present invention. In each of these figures the tooth is shown as a whole at 56. In Figure 15, the major body portion of the tooth 56 is provided with a depression, recess or slot 57 which has an enlarged portion 57a at the base thereof. In Figure 16, the body portion 56 is shown as provided with a depression, recess or slot, shown as a whole at 58, which has irregular defining wall portions 58a. In Figure 17, the major body portion 56 is provided with a slot, shown as a whole at 59, having irregular defining wall surfaces 59a. This slot is generally like the slot 58 of Figure 16 except that it extends transversely from the lingual face or side of the tooth toward the labial face or side thereof. The recesses or slots 57, 58 and 59 are adapted to receive tooth mountings in the same manner as are the teeth 37 and 43 of the preceding views. By virtue of the particular types of depressions or slots employed, some additional advantages in bonding together of the pre-configured major body portion of completely-polymerized resin and the minor body portion of non-completely-polymerized resin such as the monomer type bonding medium herein-mentioned are obtained due to the slot-defining irregular wall surfaces. It will be understood that with the slot formations of the teeth of Figures 15 to 17, inclusive, the monomeric bonding medium employed for securing the tooth to the mounting substantially conceals and envelops the mounting so as to provide an artificial tooth whose external surfaces or faces are all substantially tooth-simulating.

In connection with an artificial tooth formed, for example, from monomeric methyl-methacrylate, where it is desirable to keep the thus formed tooth over a long period of time in a place which might be too warm for this type of monomeric material, I employ an inhibitor such, for example, as a hydrochinon or pyrogallop. These reducing agents are preferably used in from 0.01 to 0.05 per cent by weight. In connection with the monomer type bonding medium, the catalyst which I employ for the purpose of causing polymerization is preferably benzoyl peroxide in proportions by weight of the monomer in from approximately 0.10 to 0.50 per cent.

Referring now particularly to Figures 18 to 30, inclusive, of the drawings, I have shown in these figures several modified forms of mounting means or members embodying my invention which are particularly well adapted for supporting the plastic artificial tooth structure of my invention. It will be understood that each of these mountings is adapted to fit into a similarly shaped depression, recess, slot or opening formed in the plastic artificial tooth, with the tooth being bonded and thus locked or clamped in position to the mounting in substantially the same manner as I have outlined above in connection with the use of the mounting 45 shown in the preceding views.

In Figure 18, the mounting comprises a frame 60 having substantially triangular portions or sections 61 providing an integral structure. The upright end and intermediate frame portions of the sections 61 are interconnected by struts or web members 62 to provide therebetween a series or plurality of spaces or openings 63. Thus, the

mounting of Figure 18 presents, in effect, a latticework-like structure, the spaces 63 being adapted to receive the monomeric type bonding means as described above.

In Figure 19 another form of suitable mounting is shown. This mounting comprises a skeleton-like frame structure 64 whose base portion extends inwardly and upwardly toward the top frame portion and terminates, as shown, in an apex 64a. The space within the frame 64 is adapted to be filled with the monomeric type bonding medium previously described.

In Figure 20 I have shown a metal mounting 65 which is substantially A-shaped, the inner edges of the leg portions 66 thereof being serrated at 67 to thus provide a better or more effective bond for the monomeric type bonding medium upon its polymerization with the similar plastic material from which the tooth structure is formed.

In Figure 21 my improved mounting is of substantially T shape and is shown as a whole at 68. The outer edges of the leg portion 69 of the T are serrated at 70.

In Figure 22 there is shown a further modified form of artificial tooth mounting embodying my invention. In general shape, this mounting is similar to the mounting 64 of Figure 19 and comprises a frame 71 preferably of rectangular cross section. Instead of having an opening or space extending through the frame, this mounting is provided with a centrally disposed partition or web portion 72 to provide on opposite sides of the mounting, similar recesses or depressions for receiving the monomeric bonding medium.

In Figure 23 I have shown another modified form of artificial tooth mounting embodying my invention. In this form, the mounting comprises a body portion 73 in the form of a substantially U-shaped frame having a central depending leg portion 74 from one face of which a centrally disposed rib 75 projects. The end portions of the frame 73 are in the form of similarly depending legs 76 which are extended or thickened laterally to provide ribs 77 which converge in the direction of the central rib or post 75. The ribs 77, as shown, are preferably V or wedge-shaped in cross section and are provided with a series of holes or openings 78 which extend therethrough. This form of mounting is adapted to be received in a similarly formed or shaped slot or slots provided in an artificial tooth and when the monomeric bonding medium is applied to the tooth and to the mounting, it will flow by virtue of its plastically fluid quality and extend through the holes or openings 78 and, when completely polymerized in complementing contiguity with the plastic of the major body portion of the tooth, will serve to lock or bind the entire tooth rigidly to the mounting.

I have shown in Figure 24 another modified form of mounting embodying my present invention. In this form, the mounting comprises a body portion 79 of substantially oblong shape having projecting from opposite ends and from the same face thereof, preferably the inner face, a pair of rib members or flanges 80 which, as shown, are of V or wedge-shaped cross section. Each of the ribs or flanges 80 is provided with several holes or openings 81 which the monomeric type bonding medium will penetrate upon application of the medium to the mounting and to the preformed slot or recess formed in the tooth which receives the mounting, to ultimately lock or bind the tooth securely to said mounting.

In Figure 25 there is shown another modified form of mounting embodying my invention in which the mounting comprises a substantially U-shaped body portion or frame 82 from the depending legs 83 of which extend flanges 84 and 85 terminating in post-like portions 86. As shown, the post-like portion 86 formed on the flange 84 is provided with a series of slots or openings 87, whereas the flange 85 is provided with a series of holes or openings 88. When the mounting is applied to an artificial tooth, the slots or openings 87 and 88 will receive the monomeric type bonding medium which is applied to the mounting and to the slot or recess formed in the tooth in which the mounting is located.

In Figure 26 there is shown another form of mounting embodying my invention for use in connection with an artificial tooth also embodying my present invention. The mounting of this figure is provided with an oblong or bar-like body portion or base 89 which, as shown, is of substantially square cross section. Extending from one face of the body portion 89 at substantially the center thereof is a projecting member or rib 90 which terminates in a substantially round or post-like portion 91. The mounting of this figure is adapted to be used similarly to those of the preceding views, it being understood that the mounting is adapted to be applied to an artificial tooth having slots or recesses corresponding generally to the shape of the mounting for receiving said mounting.

In Figure 27 another form of mounting embodying my invention is shown. In accordance with this form of the invention, the mounting comprises a metallic rectangularly shaped and relatively thin body portion or base 92 through which extends a series or plurality of holes or openings 93. From the rear face of the body portion there extends a rib or projection 94 whose outer end terminates in a substantially round or post-like portion 95. It will be understood that the mounting of this figure is adapted to be engaged with conversely formed slots or recesses in the artificial tooth applied to the mounting and that when the monomeric bonding medium is applied to the tooth and mounting, portions of it will penetrate and extend through the holes or openings 93 to firmly lock the artificial tooth to the mounting when the medium and the temporarily softened portions of plastic from which the tooth is formed, are completely polymerized.

In Figure 28 there is shown still another modified form of mounting embodying my invention. This mounting comprises a rectangular, relatively thin and flat body portion or member 96 having formed therein a plurality of rows of holes or openings 97. It is to be noted that the holes 97 are substantially frusto-conical in shape, the diameter of each of the holes being greater at the front face of the body portion than at the rear face thereof as represented by the reference characters 98 and 99, respectively. When the mounting of this form is positioned within a pre-formed slot or recess of an artificial tooth, the monomeric type of bonding medium which is applied to the slot and to the mounting, will enter the frusto-conical openings 97 so that, upon its complete polymerization, the plastic will extend into and through the openings to provide an integral mass and thus securely lock or bind the plastic artificial tooth to the mounting.

In Figure 29 there is shown another modified form of artificial tooth mounting in accordance with my present invention. The general shape of

the mounting shown in this figure is similar to the mounting 45 of Figure 8. The instant mounting comprises a body portion 100 which, as shown, is of substantially rectangular form and which is relatively thicker than the previously described mountings. The body portion 100 is provided with a pair of generally triangular holes or openings 101 and the base portion of the mounting is provided with a substantially wedge-shaped notch or opening 102 located below the central upright web or leg portion 103 which separates the openings 101. This particular mounting, which has relatively greater bulk than the preceding mountings, is adapted for use in connection with a relatively large tooth such, for example, as a molar. It will be noted that the front and rear faces of the mounting are slightly concave lengthwise as indicated at 104 and 105. By so forming the mounting, when the same is received in the slot of an artificial tooth, there will be a space provided of gradually increasing depth from the end edges 106a of the mounting toward the center thereof and between the front and rear faces of the mounting and the adjacent walls of the slot in the tooth, for the reception of the monomeric type of bonding medium which is applied to the major body portion of the tooth and to the mounting to bind the two together. As in the preceding forms, the bonding medium enters and fills the openings 101 as well as the space at the front and rear faces of the mounting. When completely polymerized, this bonding medium forms with the plastic of the tooth body, a one-piece homogeneous integral plastic tooth structure so that the bonding medium is indistinguishable from the rest of the tooth.

Another modified form of artificial tooth mounting is shown in Figure 30. The mounting herein shown comprises a body portion 106 having two separate substantially U-shaped holes or openings 107 formed therein. The front face of the mounting is convex in its mesio-distal dimension as shown at 108, the rear face of the mounting being similarly convex in shape, as shown at 109. When the mounting of Figure 30 is in place within a slot formed in an artificial tooth, spaces are provided between the walls of the slot and the adjacent front and rear faces of the mounting, which spaces are of somewhat greater depth at the portions adjacent the end edges 106a of the mounting and gradually diminish in depth toward the central leg or web 110 of the mounting. When a monomer type of bonding medium is applied in complementing contiguity with the slot in the tooth, and to the mounting, it will fill the spaces at the opposite faces of the mounting, as well as the holes or openings 107 formed therein. When polymerized with the plastic of the tooth body, the plastic of the minor body portion of the tooth structure will extend through the openings and rigidly bind or lock the tooth to the mounting. As in the form of Figure 29, the mounting 106 is adapted for use particularly with an artificial tooth of a larger type, such as a molar, and provides a very substantial mounting for such a tooth.

From the foregoing it will be seen that I have provided a new and improved interchangeable integral one-piece plastic artificial tooth which is capable of being applied to a mounting and securely locked or held to the mounting by the application of a suitable monomeric type of bonding medium corresponding to the plastic from which the major body portion of the tooth body is formed, in which the monomeric bonding medium

is homogeneous with and indistinguishable from the major body portion of the tooth body upon polymerization, and in which all exterior surfaces or faces of the ultimate artificial tooth are substantially tooth-simulating.

Moreover, it will be seen that I have provided several forms of improved mountings for use in connection with artificial teeth, all of which mountings are so formed and proportioned as to lend themselves readily to the reception of a monomeric type of bonding medium which, upon complete polymerization, becomes an integral part of the tooth body to rigidly hold or lock said tooth body to the mounting.

It will be understood that various kinds of plastics may be employed in connection with the manufacture of artificial teeth in accordance with my invention. It is only necessary that a monomeric type of bonding medium which corresponds to the type of plastic from which the tooth body is formed, be used, so that upon polymerization of the bonding medium and the polymerization of the temporarily softened portion of the plastic of the tooth body, the plastic of the preconfigured tooth body and that of the minor body portion of monomeric bonding medium will combine by molecular union as one and the same to provide an homogeneous one-piece plastic artificial tooth structure.

It is to be understood that while I have mentioned specifically the use of one type of plastic, namely resin known as methyl-methacrylate, and have also mentioned only several kinds of suitable catalysts, solvents and inhibitors, various other types of plastics, catalysts, solvents and inhibitors may be employed within the purview and scope of my present invention.

It will be understood further that while I have not illustrated it in the drawings, an artificial tooth made in accordance with my present invention may be ground down on its mesial and distal sides or edges if and when desired, for the purpose of providing an accurate fit between other teeth.

Having thus described my invention, what I claim is:

1. An anchoring device for supporting an artificial plastic interchangeable tooth, comprising a frame portion having a pair of integral substantially triangular sections, and spaced substantially parallel web portions in each of the triangular sections providing a plurality of independent openings in said sections adapted to receive portions of the plastic from which the tooth is formed to hold the tooth to said device.

2. An artificial-tooth-forming element for a prosthetic dental appliance, comprising: a major body portion of rigid substantially completely-polymerized synthetic resin having its surfaces configured in simulation of the natural tooth to be replaced thereby, a minor body portion complementing said major body portion and formed of synthetic resin in a non-completely-polymerized state having the quality of plastic flow under manually-imposable stress and having the property of homogeneous molecular union with the resin of said major body portion when subjected to complete polymerization in complementing contiguity therewith, and a tooth-mounting member having a portion received in said minor body portion for fixed embedded anchorage therein when complete polymerization of the resin thereof is effected, said mounting member being of a form such as to be adjustable in said minor body portion by manipulation preliminary

to said complete polymerization of its resin enabling precise mesial, distal, labial, lingual, gingival and incisal orientation of said configured major body portion preliminary to final incorporation of the structure as an ultimate completely-polymerized tooth component of the appliance.

3. An artificial-tooth-forming element for a prosthetic dental appliance, comprising: a major body portion of rigid substantially completely-polymerized synthetic resin having its surfaces pre-configured in simulation of the natural tooth to be replaced thereby, a minor body portion complementing said major body portion and formed of synthetic resin in a non-completely-polymerized state having the quality of flow under manually-imposable stress and having the property of homogeneous molecular union with the resin of said major body portion when subjected to complete polymerization in complementing contiguity therewith, said minor body portion being of a size, form and arrangement relative to said major body portion enabling insertion and embedding of the tooth-anchoring portion of a tooth-mounting member of the appliance therein and manually-adjusted precise mesial, distal, labial, lingual, gingival and incisal orientation of said pre-configured major body portion immediately prior to final incorporation of the structure as an ultimate completely-polymerized tooth component of the appliance.

4. An artificial-tooth-forming element for a prosthetic dental appliance, comprising: a major body portion of rigid substantially completely-polymerized synthetic resin having its most evident functional surfaces pre-configured in simulation of the natural tooth to be replaced thereby and having its relatively non-evident portion provided with a recess extending well into said body portion, a minor body portion disposed in said recess complementing said major body portion and formed of synthetic resin in a non-completely-polymerized state having the quality of plastic flow under manually-imposable stress and having the property of homogeneous molecular union with the resin of said major body portion when subjected to complete polymerization within the recess of said major body portion, said minor body portion being of a volume and fluidity enabling penetrative keying of its mass into and around the therein-embedded anchor portion of a tooth mounting member receivable and shiftable in the recess of said major body portion incident to precision mesial, distal, labial, lingual, gingival and incisal orientation of said pre-configured major body portion immediately prior to final incorporation of the structure as an ultimate completely-polymerized tooth component of the appliance.

to said complete polymerization of its resin enabling precise mesial, distal, labial, lingual, gingival and incisal orientation of said configured major body portion preliminary to final incorporation of the structure as an ultimate completely-polymerized tooth component of the appliance.

3. An artificial-tooth-forming element for a prosthetic dental appliance, comprising: a major body portion of rigid substantially completely-polymerized synthetic resin having its surfaces pre-configured in simulation of the natural tooth to be replaced thereby, a minor body portion complementing said major body portion and formed of synthetic resin in a non-completely-polymerized state having the quality of flow under manually-imposable stress and having the property of homogeneous molecular union with the resin of said major body portion when subjected to complete polymerization in complementing contiguity therewith, said minor body portion being of a size, form and arrangement relative to said major body portion enabling insertion and embedding of the tooth-anchoring portion of a tooth-mounting member of the appliance therein and manually-adjusted precise mesial, distal, labial, lingual, gingival and incisal orientation of said pre-configured major body portion immediately prior to final incorporation of the structure as an ultimate completely-polymerized tooth component of the appliance.

4. An artificial-tooth-forming element for a prosthetic dental appliance, comprising: a major body portion of rigid substantially completely-polymerized synthetic resin having its most evident functional surfaces pre-configured in simulation of the natural tooth to be replaced thereby and having its relatively non-evident portion provided with a recess extending well into said body portion, a minor body portion disposed in said recess complementing said major body portion and formed of synthetic resin in a non-completely-polymerized state having the quality of plastic flow under manually-imposable stress and having the property of homogeneous molecular union with the resin of said major body portion when subjected to complete polymerization within the recess of said major body portion, said minor body portion being of a volume and fluidity enabling penetrative keying of its mass into and around the therein-embedded anchor portion of a tooth mounting member receivable and shiftable in the recess of said major body portion incident to precision mesial, distal, labial, lingual, gingival and incisal orientation of said pre-configured major body portion immediately prior to final incorporation of the structure as an ultimate completely-polymerized tooth component of the appliance.
